UNITED STATES PATENT OFFICE.

CHARLES WARREN STEVENS, OF BEEBE PLAIN, QUEBEC, CANADA, ASSIGNOR OF ONE-HALF, BY MESNE ASSIGNMENTS, TO ALONZO A. HOUSE, OF BRISTOL, OHIO.

MEAT AND VEGETABLE SLICING MACHINE.

SPECIFICATION forming part of Letters Patent No. 352,101, dated November 2, 1886.

Application filed January 9, 1885. Renewed September 15, 1886. Serial No. 213,636. (No model.) Patented in Canada January 26, 1885, No. 20,981.

To all whom it may concern:

Be it known that I, CHARLES WARREN STEVENS, a citizen of the United States, and a resident of Beebe Plain, in the county of Stanstead, in the Province of Quebec, Canada, have invented an Improvement in Meat and Vegetable Slicing Machines, of which the following description, in connection with the accompanying drawings, is a specification, like letters on the drawings representing like parts.

This improvement in meat and vegetable slicing machines has for its object to simplify and perfect the construction of the operating parts of the gage-board, to obtain an easy yet steady oblique adjustment of said gage-board with relation to the knife; second, to provide a simple and durable slicing-machine having a folding head-board and swinging gate, and which may be readily folded and compactly arranged one part upon another, to occupy as little space as possible when not in use.

In this my improved slicer the knife-holder, provided with the usual obliquely-arranged knife and gage-board, slides in ways in the usual holder-frame, which I shall hereinafter designate as the "slide-frame," the latter being hinged to the table or base. The table is provided with a head-board hinged thereto and extended in between the uprights and top and bottom pieces of the slide-frame, so that its inner end will be brought into required relation with the path of movement of the knife, the said inner end being faced with metal on one side and provided with a rabbet at its other side to be fitted to the adjacent upright of the slide-frame when elevated to a vertical position. Further, I provide a removable swinging gate to operate in connection with the folding or hinged head-board, to enable the articles to be fed to the knife thereby, instead of with the hand. The standard forming part of the removable swinging gate has a pin at its lower end to enter an orifice in the table, and a reduced portion or extension at its upper end to bear against the top of the slide-frame in such manner as to allow the gate to be moved

in between the top and bottom of said slide-frame and cause all of the article placed on the table to be thoroughly fed to the knife to be cut. The gate itself is provided with a stop or projection to engage the top of the slide-frame, and thereby limit the movement of the gate toward the knife and prevent it from being forced into the path of movement of said knife. The knife-holder is adapted to slide in the slide-frame, and is provided with a gage-board and the usual stationary board, to which the obliquely-arranged knife is secured. The gage-board is attached to the knife-holder in required relation with the knife by means of a wing arranged at the heel of the gage-board and adapted to move in an oblique groove in the knife-holder, and by two slotted arms attached to the beveled end of said gage-board and retained by headed screws or studs to the beveled portion of the end piece of the knife-holder. For operating mechanism, the gage-board has a screw-rod fixed to a plate pivoted to a sector, which latter is attached to the end piece of the knife holder, the said screw-rod having a washer and a screw-knob, which, upon being turned, binds the washer to the sector and retains the screw-rod in required adjusted position to said sector. A link pivoted at one end to a bracket on the gage-board and at the other end to the pivoted plate enables the gage-board to be moved and adjusted as the screw-rod is moved on the sector. One of the way-pieces is adjusted to the slide-frame, so as to provide for wear of parts.

The invention is more fully set forth in the following description, and is particularly pointed out in the claims.

Figure 1 is a front elevation of a slicing-machine embodying my invention; Fig. 2, a plan view thereof; and Fig. 3, a section on line *xx*, Fig. 2, the swinging gate having first been removed. Fig. 4, a detail in perspective looking from the rear of the machine, and showing the part *P* open; Fig. 5, details which will be referred to hereinafter.

The open rectangular slide-frame, consisting of the top and bottom pieces, *a a'*, and ends or

uprights b b' , is hinged at e to the table A, which is provided with the usual cross-bars, d d' , the latter cross-bar having a rabbet to engage the edge of a kitchen table or stand, C, when in use.

The table A has an extension, 2, faced with thin sheet metal and projecting into the slide-frame the depth of the uprights b b' , so as to be brought into proper relation with the path 10 of movement of the knife R. The head-board B is hinged at e to the top of the table, and the end next the slide-frame projects into said frame a distance equal to the thickness of the uprights, and is rabbeted, as at f , to fit the adjacent upright b' , as shown, to serve as a brace 15 to hold the hinged slide-frame in vertical position. A pin, 3, projects from the upright b' and enters an opening in the hinged head-board, to further retain the latter in elevated 20 position.

The top and bottom pieces of the slide-frame are provided along their faces with guides or way-pieces t t' , which enter grooves cut in the top and bottom of the knife-holder D, to retain 25 it to the slide-frame and permit the same to slide therein. The lower strip or guide, t' , is adjustably secured to the bottom a' of the slide-frame by means of the set-screws 4, passing through slots in said guide-piece, whereby 30 the guide may be adjusted to compensate for wear of parts.

The knife R is secured in oblique position to the knife-holder D, having a handle, y , while the obliquely-adjustable gage-board E is adjustably supported in the space between the 35 knife and end piece, H, by means of a wing or rib, g , of an L shape in cross-section. This wing having a bent end, g' , is secured to the heel of the gage-board and works in the groove 40 g'' in the bottom of the knife-holder, the latter being faced at the groove with a plate, g^3 , having an L-shaped slot, 7, and adjustably attached to the knife-holder by means of headed 45 screws 6, passing through slots in the plate g^3 , as shown. The plate g^3 may thus be adjusted to compensate for wear of parts, whereby that 50 end of the gage-board is steadily retained in position—a provision necessary, since looseness thereof prevents the cutting of even regular 55 slices from the articles that may be fed to the knife. The bent end g' of the wing g limits the inward movement of the gage-board toward the knife by engaging the plate g^3 .

The front or larger end of the gage-board is 55 beveled and provided with two slotted arms, h , secured thereto, so that the beveled end will ride on the similarly-beveled portion of the end piece, H, which latter is provided with headed screws h^2 , entering the slotted arms h , 60 to retain the gage-board to the end piece, and yet allow adjustment thereof.

The oblique adjustment of the gage-board with relation to the knife is accomplished by means of a screw-rod, i , firmly secured in the 65 present instance to a plate, k , pivoted to a sec-

tor, m , attached to the end piece, H, while a connecting-link, p , is pivoted to the plate k and to the bracket n , fastened to the gage-board, as shown.

The screw-rod projects beyond the curved 70 edge m' of the sector m , and receives an L-shaped washer, n' , to lap over the edge m' , and a screw-knob, o , adapted to be turned on the screw-rod to bind the washer to the edge m' , and thereby hold the said rod to the sector at 75 any desired point.

By adjustment of the screw-rod to the sector at any desired point, the gage-board, through the connecting-link p , is moved obliquely toward or from the knife, whereby any required 80 position is quickly and easily attained, it being necessary simply to slightly unscrew the screw-knob, move the rod along the sector in the proper direction, and then tighten the parts. With the aid of this simple mechanism the 85 gage-board is firmly held in adjusted position parallel with the plane of movement of the knife, whereby slices are uniformly cut of any desired thickness from the article fed to said knife.

The swinging gate P, having an attached post p' , is removably mounted on the table A by means of a pin, p^2 , (shown in dotted lines, Fig. 1,) at the lower end of the post, entering a hole or socket, p^3 , (shown in Fig. 3,) in said 90 table. The upper end of the post is reduced, as at r , and the gate itself is provided with the stops s , both of which engage the top of the slide-frame when the gate is moved therein, to prevent said gate from being forced into the 100 path of movement of the knife R, while at the same time they retain the gate within the slide-frame parallel with the knife, whereby all of the article placed on the table may be fed to the knife and sliced.

What I claim is—

1. The combination, in a slicing-machine, with a table, a connected vertical slide-frame having a knife-holder with knife, and a head-board hinged to the table, of a swinging gate 110 provided with a post removably mounted in the table, as specified, and having a reduced portion at its upper end, and a stop attached to the top of said gate, whereby the gate may be moved into the slide-frame in close proximity to the knife, as specified.

2. The combination, with a knife-holder provided with a knife and L-shaped groove g'' , and the plate having an L-shaped slot, the elongated screw-slots, and the holding screws 120 passing through the screw-slots and into the knife-holder, of a gage-board provided at its smaller end with the wing g , having bent portion g' , and mechanism at its larger end to move the gage-board in and out of the knife-holder, substantially as set forth.

3. The combination, with a knife-holder provided with a sector and a swinging screw-rod and retaining means to hold the screw-rod 125 at various points to the sector, of a movable 130

gage-board and a connecting-link, as and for the purpose specified.

4. The knife-holder provided with a knife and movable gage-board, combined with a sector mounted on the knife-holder, a pivoted plate provided with a screw-rod having a washer and adjusting-knob, and a pivoted connecting link, all as set forth.

In testimony whereof I have signed my name to this specification in the presence of two subscribing witnesses.

CHARLES WARREN STEVENS.
